UNITED STATES PATENT OFFICE.

OTTO BANNER, OF EASTON, PENNSYLVANIA, ASSIGNOR TO INGERSOLL-RAND COMPANY, OF JERSEY CITY, NEW JERSEY, A CORPORATION OF NEW JERSEY.

STEAM-TURBINE.

1,161,436.

Specification of Letters Patent. Patented Nov. 23, 1915.

Application filed April 10, 1914. Serial No. 830,845.

To all whom it may concern:

Be it known that I, OTTO BANNER, a subject of the German Emperor, residing at Easton, in the county of Northampton and 5 State of Pennsylvania, have invented a certain new and useful Improvement in Steam-Turbines, of which the following is a specification.

This invention relates to steam turbines 10 and more particularly to the construction of turbines adapted for use with high pressure steam with or without supplemental low pressure steam.

The object of this invention is to provide 15 a turbine of this type which will be of simple and economical construction, compact in size and adapted to operate with a high comparatively constant efficiency through a large range of loads.

20 These objects are accomplished by the turbine, a practical embodiment of which is shown in the accompanying drawings, in which,

Figure 1 shows a longitudinal section 25 through a portion of the turbine taken on the line 1—1 of Fig. 2, and Fig. 2 shows a horizontal section through the high pressure wheel taken on the line 2—2 of Fig. 1.

The turbine, as shown, comprises a casing 30 1 which has, at its outer end, a high pressure steam chamber 2. Inwardly of this chamber 2 the casing is reduced in diameter forming a series of low pressure chambers 3, 4, 5 and 6, and others, not 35 shown, which are separated from the high pressure chamber 2 and from each other by diaphragms 7, 8, 9 and 10, the chambers 5 and 6 being shown of greater diameter than 3 and 4, although this is not essential.

40 In the high pressure chamber rotates a single bladed high pressure wheel 11 which receives steam through a nozzle 12 communicating with a high pressure steam chest 13 which is placed on the inner face of the

45 larger diameter of the casing and thus does not increase the necessary dimensions of the casing in any direction. A balanced valve 14, of ordinary construction, controls the admission of steam from the steam chest 13 to the nozzle 9, steam being admitted to the steam chest through a pipe 15.

The valve 14 is operated from the governor of the turbine, not shown, by any suitable regulating mechanism 16, the details of

which form no part of the present invention, and may be as shown in my previous Patent No. 1,117,306 granted November 17th, 1914.

The steam from the nozzle 9 passes through the blades of the wheel 8 toward 60 the outer end of the turbine and is received by a reversing passage 17 of ordinary construction, which is provided as usual with guiding vanes 18. This reversing passage 65 17 directs the steam again through the high pressure wheel to the inner side of the wheel, from thence it can pass directly and without any impedance through the nozzles 19 in the first low pressure wheel 20 and thence through the nozzles 21, 22 and 23 and 70 their respective low pressure wheels to the exhaust of the turbine.

By means of this construction, a very compact and economical turbine can be manufactured and one of high comparatively constant efficiency through a large range of loads by reason of the fact that steam passes more than once through the high pressure blades thus fractionally abstracting the velocity of the high pressure 80 steam which then passes without hindrance to be further expanded in the low pressure nozzles.

Although the turbine is here shown with a single nozzle and reversing passage, it is 85 obvious that more than one nozzle and reversing passage therefor may be used without departing from my invention and furthermore, the steam may be passed more than twice through the high pressure wheel 90 by the reversing passages without invention and it is to be understood that the present showing and description discloses only one specified modification of my invention and other forms and modifications are included 95 in the spirit and scope of the invention as expressed in the claim.

What I claim is:

In a steam turbine, a casing having a high pressure chamber at one end, and low pressure chambers of smaller diameter communicating therewith, a single bladed high pressure wheel in said high pressure chamber, a steam chamber on the inner side of said high pressure chamber, having a nozzle 100 for directing steam through said high pressure wheel toward the end of the turbine, a reversing passage for redirecting 105

the steam in the opposite direction through said high pressure wheel, a series of low pressure wheels in said low pressure chambers and nozzles for directing steam from 5 the high pressure chamber through said low pressure wheels in the same direction as said reversing passage.

In testimony whereof, I have hereunto set my hand.

OTTO BANNER.
